UNITED STATES PATENT OFFICE.

HENRY PARSONS, OF MARLBOROUGH, MASSACHUSETTS.

ELEVATOR.

SPECIFICATION forming part of Letters Patent No. 417,274, dated December 17, 1889.

Application filed April 8, 1889. Serial No. 306,834. (No model.)

To all whom it may concern:

Be it known that I, HENRY PARSONS, of Marlborough, in the county of Middlesex and State of Massachusetts, have invented a new and useful Improvement in Elevators, which will, in connection with the accompanying drawings, be hereinafter fully described, and specifically defined in the appended claims.

In said drawings, Figure 1 is a top plan view of the elevator hoisting devices complete as assembled for use. Fig. 2 is a sectional elevation, the section being vertical and taken on line Z, Fig. 1, and the elevation as viewed from the near edge of the sheet when it is turned to the right. Fig. 3 is a sectional elevation, the section being vertical and taken on line X, Fig. 1, and the elevation as viewed from the near edge of the sheet when it is turned to the right. Fig. 4 is a sectional elevation, the section being vertical and taken on line W W, Fig. 1, and the elevation as viewed from the right in that figure when the sheet is turned to the right. Fig. 5 is a detail of a part shown in Fig. 4, to be explained. Fig. 6 is a sectional elevation, the section being vertical and taken on line V, Fig. 1, and the elevation as viewed from the right when the sheet is turned to the right. Fig. 7 is a sectional elevation, the section being vertical and taken on line T, Fig. 1, and the elevation as viewed from the left when the sheet is turned to the right. Fig. 8 is an elevation showing a detail of one of the belt-shipping devices. Fig. 9 is an elevation showing a detail of one of the "stops." Fig. 10 is a horizontal section taken through the axis of the parts shown in Fig. 9, as when they are assembled. Fig. 11 is a side elevation of a portion of the gear-casing. Fig. 12 is a detached perspective view of the clutch-shipper fork and its weighted lever.

This invention relates to that part of freight and passenger elevators by which the "cage" or "carriage," as it is indifferently termed, is raised and lowered, which said part consists, essentially, of a drum for the hoisting-rope, a gearing by which the drum may be rotated in both directions, with pulleys for actuating said gearing, a belt-shipping device operated by hand, a brake, and an automatic belt-shipping device to stop the machine when the elevator reaches its highest or lowest intended

limit; and my invention consists in means whereby, through the slackening of the hoisting-rope from any cause, the then driving-belt will be automatically shifted to a loose pulley, the brake applied, and the uncoiling of the rope from the drum instantly stopped, as will, in connection with said drawings, be hereinafter fully described, and pointed out in the claims.

Referring again to said drawings, A represents the bed or frame of the hoisting apparatus, and B is the grooved rope-carrying drum secured on arbor b d, journaled in suitable bearings on said frame, as shown. A tangent-wheel E is shown as bolted to the end of drum B, Fig. 2, said wheel being covered by the housing or casing 16, which in Fig. 2 is broken away to show said wheel, as also the enmeshing endless screw F, usually formed as an integral part of its arbor G, which is duly supported in proper journal-bearings in frame A, as shown, said tangent-wheel and endless screw constituting the well-known "worm-gear," by which the drum is rotated in either direction, according as it is desired to either raise or lower the cage, by means of rope a, that is secured to the cage and is wound upon and unwound from the drum. Said endless screw is thus driven by means of "fast" pulley C and loose pulleys D D on arbor G and the usual two belts arranged on said pulleys and running in opposite directions, in a well-known manner, it being obvious that when either belt is on fast pulley C the drum will then be driven in accordance with the direction of movement of such belt, that when either belt is on pulley C the other belt is on its loose pulley D, and that when both belts are on their respective loose pulleys then the machine is inoperative; and for the purpose of thus "shipping" the belts, as desired, the following devices are employed: Two belt-forks 20 are rigidly secured upon their respective shipper-bars t, which at their outer ends slide in the supports 21, while at their inner ends they are pivoted to the head of rocking levers n, which are loosely mounted on shaft s, while above shaft s is journaled the shipper-shaft d, which carries the cams m m, rigidly secured upon it. In the side of each of said cams is formed a groove p, in which is

inserted a pin *q* of the levers *n*, said groove being concentric to the axis of shaft *d* except at one of its terminals, where it converges toward the shaft, as shown in Figs. 3 and 8, said 5 cams being so set upon their shaft and reversed in their position relatively to each other that either belt may be moved onto fast pulley *C* or both may be moved onto their respective loose pulleys, it being obvious and 10 well known that neither lever will be rocked by the rotation of its cam except when the pin *q* on the lever is moving in the converging portion of the cam-groove, and when said pins are in the concentric portion of their 15 respective grooves then the belts are on their respective loose pulleys, and hence by rocking the shaft *d* in the proper direction the intended belt may be moved onto the fast pulley. A stop-cam *k*, Fig. 5, being secured 20 on said shaft *d* and arranged to engage a stop *l*, that rises from bed *A*, and so adjusted relatively to cam *k* that when shaft *d* has been rotated in either direction to the extent that the belt being shipped is evenly on the fast 25 pulley *C*, said stop will be encountered by the cam *k* and the rotation of the shaft arrested.

In order to rotate shaft *d* by hand, either to start or stop the cage, a pulley *e* is secured on shaft *d*, and an endless shipping-cord 30 placed thereon extends down the well through the cage and passes over a pulley at the bottom of the well, and is thus accessible to the operator who runs the elevator, who, by drawing said cord in the proper direction, can, by 35 means specified, bring either belt onto or off the fast pulley.

For the purpose of automatically unshipping the belt from the fast pulley when the cage reaches the highest or lowest limit, a 40 sprocket *f* is mounted to slide lineally on shaft *d*, but is interlocked therewith by a "spline," "key," or "feather," as it is indifferently termed, which enters a keyway or slot cut in each, such slot extending preferably the length of the shaft, as shown in Fig. 45 1. Said sprocket is engaged and driven by an endless chain *g*, that engages and is intermittently driven by sprocket *h*, threaded on shaft *b*. On each plane of sprocket *h* is a 50 stud 24, which are respectively engaged by the stud 22 on disk *i* and stud 23 on disk *j*, which disks revolve fixedly with shaft *b* of the drum. It is obvious that if shaft *d* be held from rotation and shaft *b* is rotated, 55 chain *g* being held quiescent by means of sprocket *f*, splined to its shaft, in such case sprocket *h* will move toward disk *i* or *j*, according to the direction in which shaft *b* is being rotated, and that hence, when the 60 stud on sprocket *h* comes in contact with the stud on the disk that it is approaching, the chain will rotate shaft *d*, and through the means already described will ship the then driving-belt from the fast to the loose pulley, 65 and so stop the machine.

For the purpose of locking drum *B*, and consequently holding immovable the cage

that is therefrom suspended, a brake-wheel *c* is rigidly secured on shaft *G*, and is inclosed by a friction-band 10, secured at its lineal center to support 11, and at its ends attached to ears of lever 8, arranged on opposite sides of its pivotal support 12, secured in standard 13, as shown in Fig. 6, so that when said lever is forced downward by its weight 9 said band 70 is thereby constricted upon the wheel and brakes the same. To raise said brake-lever and its weight, I rigidly secure on shaft *s* an angle-lever 5, the horizontal arm of which is connected with lever 8 by a short stirrup or 80 link 7, while its upper arm carries a trundle 6, that bears upon the peripheral face of cam 4, secured on shaft *d*, said cam having a depression at one point in its periphery, into which the said trundle in lever 5 can retire, 85 as shown in Fig. 3, so that its horizontal arm may descend and thereby allow the brake weight and lever to lock wheel *c*, and thus stop the drum *B* and the movement of the cage, as stated, said cam 4 being so "set" or 90 positioned on its shaft as that the brake will be applied to stop the machine immediately after the driving-belt has been shipped upon its loose pulley.

For the purpose of properly adjusting disks 95 *i* *j* in order that their projections may interlock with the projections on sprocket *h* at the desired point of its movement, said disks have a certain number of bolt-holes near their periphery, (see Figs. 9 and 10,) while 100 disks 25 26, which by their hubs are rigidly secured to shaft *b*, have each a different number of holes, (see Fig. 9,) either one more or one less than do disks *i* *j*; and hence, as but one bolt 27 is employed to secure disks *i* *j* to their 105 respective fast disks 25 26, therefore a very slight rotation of disks *i* *j* will bring a bolt-hole in each into coincidence for the insertion of the securing-bolt 27.

As the cage is from various causes liable to 110 be temporarily held from descending coincidentally with the uncoiling of rope *a*, by which it is suspended from drum *B*, and is also liable, after the rope has uncoiled to a limited extent, to fall and break the rope or other 115 parts, I have invented the following means by which to instantly stop the movement of the drum when the rope has thus slackened.

A sprocket *u*, secured on shaft *b* to rotate therewith, is connected by means of chain *z* 120 with sprocket *v*, that habitually revolves freely on shaft *d*, but which is toothed upon one plane or side, and when slid into engagement with the correspondingly-toothed clutch *w*, rigidly secured on shaft *d*, will insure the rotation 125 thereof, thereby through the means already described shifting the belt to the loose pulley and applying the brake. To thus slide sprocket *v* into engagement with clutch *w*, I employ a forked angle-lever *x*, the prongs of which engage in a concentric groove in the hub of the sprocket, as shown in Fig. 1, said lever being pivoted by its central tubular portion 28, which is arranged on stud 29, supported in hub *y*, 130

secured to base A, Fig. 2. Formed upon or secured to said tubular portion 28 is a horizontal arm 2, provided with weight 3, of such "avordupois" that when released (as will be explained) it will move sprocket *v* into engagement with clutch *w* for the purpose already specified. To habitually support arm 2 and its weight 3, I pivot a curved lever 14 upon stud 15, secured in the casing 16 of tangent-wheel E, the lower end of said lever being formed with an angle or foot 19, upon which said weighted arm 2 is supported when the outer longer arm is supported, as shown—that is, a rod 17, rigidly secured in said arm, as shown, extends across the face of drum B parallel with its axis, and on this rod is the traveling groove-faced pulley or roll 18, engaging rope *a*, which, so long as the rope *a* is held taut by the cage, thereby supports the lever in position, as shown; but should the cage from any cause fail to descend coincidentally with the uncoiling of the rope then roll 18 and the outer arm of its lever 14 would move downward as the rope slackened to such limited extent as to allow foot 19 to be withdrawn from weighted lever 2, thereby engaging sprocket *v* with clutch *w*, when the belt would be shipped to a loose pulley, the brake applied, and the machine brought to a standstill before the rope had materially slackened or so as to allow the dropping of the car.

It is obvious that a line projected to pass through the axis of pivot 15 of lever 14 and the axis of rod 17 would be at such an angle to the vertical line of the rope as that a very slight slackening of the latter would allow the disengagement of the foot of the lever 14 from the weighted lever 2.

Instead of supporting rod 17 at one end only, as shown, it may be supported at both ends by means of two levers 14, rigidly united or formed integrally, in both which levers said rod would be secured, and in such case but one of said levers 14 need extend below support 15, as but one need engage weighted lever 2. It will also be obvious that a plurality of ropes *a* may be employed, if preferred.

I am aware that it is common to arrange a lever beneath the hoisting-rope drum to be actuated by the weight of the hoisting-rope when slackened, so as to bear upon said lever, which latter is arranged to actuate a

clutch by which the belt will be unshipped from the driving-pulley; but my invention is altogether unlike, both in its construction and mode of operation, such old device, as my device is rendered operative by the mere slackening of the rope, and will operate with equal certainty at all times if the rope slackens, while said older device depends for its efficiency upon the rope resting upon the lever, and hence will not operate when the amount of rope depending in the well below the sustaining-sheave is greater than that between said sheave and the drum, as such depending portion will in that case hold the other taut and prevent its resting upon the lever to actuate the same.

I claim as my invention—

1. In an elevator, the combination of a sprocket secured on the drum-shaft, a toothed sprocket loose on the shipper-shaft, an endless chain connecting said sprockets, a clutch rigidly secured on the shipper-shaft and toothed to interlock with said toothed sprocket, a weighted lever interlocked with said toothed sprocket and arranged, when liberated, to engage said sprocket with the clutch, a lever arranged to engage and sustain said sprocket-actuating lever and carrying a traveling roll that bears against the hoisting-rope, said lever and its roll being so arranged that when the rope slackens said lever will fall and liberate the sprocket-actuating lever, whereby the shipper-shaft will be rotated, the belt shifted, and the brake applied, all substantially as specified.

2. In an elevator, the combination of a sprocket *u*, secured on drum-shaft *b*, a sprocket *v*, loosely mounted on a shipper-shaft *d* and toothed or indented at one of its sides, a chain *z*, connecting said sprockets, a toothed clutch *w*, rigidly secured on shaft *d*, the shipper *x*, engaging said toothed sprocket and having weighted arm 2 to actuate it, a lever 14, duly pivoted and formed to sustain said weighted arm, a rod 17, carried by a lever 14, and a sheave or roll 18, arranged to revolve and travel on said rod, all substantially as specified.

HENRY PARSONS.
